VEHICLE DIFFERENTIAL HOUSING

Michael D. Liddiard, 242 W. Klo Road,
Lathrop, Calif. 95330

Filed Feb. 11, 1970, Ser. No. 21,375

Term of patent 14 years

Int. Cl. D15—99

U.S. Cl. D55—1

FIG. 1

FIG. 2

FIG. 3

FIG. 1 is a front elevational view of a vehicle differential housing, showing my new design;

FIG. 2 is a side elevational view, the opposite side being substantially similar in appearance;

FIG. 3 is a bottom plan view, the top plan being substantially similar in appearance;

FIG. 4 is a fragmentary sectional view, the plane of the section being indicated by the line 4-4 in FIG. 1;

FIG. 5 is a fragmentary sectional view to an enlarged scale, the plane of the section being indicated by the line 5-5 in FIG. 1;

FIG. 6 is a rear elevational view; and,

FIG. 7 is a fragmentary sectional view to an enlarged scale, the plane of the section being indicated by the line 7-7 in FIG. 6.

I claim:

The ornamental design for a vehicle differential housing, as shown and described.
